UNITED STATES PATENT OFFICE.

MONTAGUE R. SIDWELL, OF CAMDEN, NEW JERSEY.

ORNAMENTAL CANDLE.

Application filed November 19, 1925. Serial No. 70,129.

My invention relates to an ornamental candle and more particularly to high-grade candles of the type having a wax body as distinguished from ornamental candles having wooden or metal bodies.

The general object of my invention is to provide a candle having embodied therein means that will prevent the candle from becoming deformed in the presence of abnormal heat.

A further object of the invention is to provide a candle having silk or like delicate fibers to simulate a wick terminal of a candle and having associated therewith means to protect the fibers from absorbing the wax either in casting the candle or subsequent to the casting of the candle when the candle is subjected to unusual heat as in an excessively hot room or in extremely hot weather.

Reference is to be had to the accompanying drawings forming a part of this specification, it being understood that the drawings are merely illustrative of practical examples of the invention.

Figure 1 is a view partly in side elevation and partly in section, showing a candle embodying my invention in one form;

Figure 2 is a vertical section of the top attachment to simulate an ordinary candle;

Figure 3 is a cross section on the line 3—3, Figure 2;

Figure 4 is a view similar to Figure 1 but illustrating a modification;

Figure 5 is a cross section on the line 5—5, Figure 4;

Figure 6 is a cross section similar to Figure 5 but illustrating a slight modification in the form of the core.

In carrying out my invention in practice, in accordance with the form of the invention shown in Figures 1 to 3, a candle body 10 is formed of wax and axially bored. In the bore is fitted a strengthening core 11 which in practice is usually made of wood though any other suitable material may be employed.

The core 11 terminates short of the top of the candle as clearly shown in Figure 1 and the remaining portion of the bore which is of reduced diameter receives snugly the

shank of an ornamental tip 12. The tip 12 is formed in practice of fibers and usually of silk or other fine fibers. In order that the fibers of the tip may not become deteriorated by absorbing the wax of the candle, I provide a protecting means which may consist of a metal sheath 13 receiving the bunched lower ends of the fibers which fill said sheath. The sheath 13 with the fibers therein may be molded into the candle or inserted subsequently to the molding of the candle and the boring thereof. The sheathed tip reinforces the candle at the top and completes with the core 11 a stiffening core for the wax body 10.

In the form shown in Figures 4 and 5, the candle body 110 has a rectangular axial bore which receives a four-sided core 111. The core 111 is itself bored axially and it receives a wick cord 112 of fibers extending through the core to the bottom of the candle. The fiber cord 112 is frayed as at 212 to simulate a candle wick. As a protecting means the cord 112 is covered with shellac 113, glue or the like to prevent absorption of the wax by the cord.

In the form shown in Figure 6 the candle body 110 is the same as in Figures 4 and 5 with the squared bore which receives a four-sided core 211 to receive a groove 311 which is formed on one side of the core 211 to receive a cord simulating a wick.

I would state furthermore that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. An ornamental candle including a body formed of material adapted to soften in the presence of undue heat, and a stiff core in said body, to stiffen said body and maintain the same against deformation.

2. A candle including a body formed of material adapted to soften in the presence of undue heat, said body having an axial bore

a stiffening core in said body terminating short of the top, a fibrous candle tip for said body and protective means on said tip within the candle to protect the fibers and to constitute a stiffener for the upper portion of the candle.

3. A candle including a candle body

formed of material adapted to soften in the presence of undue heat, a stiffening means within the body, fibers projecting beyond the ¹⁰ upper end of the body and extending into the same, and protective means for said fibers within the candle.

MONTAGUE R. SIDWELL.
